OSCILLATING VALVE.

SPECIFICATION forming part of Letters Patent No. 728,787, dated May 19, 1903.

Application filed December 30, 1902. Serial No. 137,152. (No model.)

To all whom it may concern:

Be it known that I, GEORGE LESLEY WACKEROW, residing at Mellette, in the county of Spink and State of South Dakota, have invented 5 certain new and useful Improvements in Oscillating Valves, of which the following is a specification.

This invention relates to oscillating valves; and the invention consists of novel and useful improvements providing increased advantage over similar valves as heretofore constructed.

More definitely stated, the invention consists of a peculiar oscillating valve extending 15 from end to end of the cylinder and a special steam-chest and arrangement of steam passages or ports.

In order to enable others skilled in the art to make and use my invention, I will now 20 proceed to describe its construction and operation with reference to the accompanying drawings, forming a part of this specification, and in which—

Figure 1 is a view in side elevation, illustrating 25 my invention, the detachable side of the steam-chest being removed and the engine-cylinder shown in section. Fig. 2 is a transverse vertical section through my invention, taken on line $x-x$ of Fig. 1. Fig. 3 is a perspective view of an engine-cylinder and my improved valve-seat.

In carrying out my invention I employ a steam-chest A, consisting of a special valve-seat B and an upper portion preferably formed 35 in two pieces—namely, a removable side plate C and a one-piece top and side D D'. The valve-seat B, side plate C, and the one-piece top and side D D' are provided with bolt-holes and flanged edges, (shown in the drawings,) adapting them to be secured together.

The valve-seat B consists of an elongated plate B', having vertically-disposed ends E. The inner side of the ends E is curved, as at F, and provided with ports F' F'', the former 45 being the inlet leading to the engine-cylinder and the latter the exhaust-ports having outlets F³, that may be opened and closed, as will be understood, by any suitable mechanism, also well understood, in operative connection with the engine.

In further carrying out my invention I employ a peculiar valve G, fixed to a rock-shaft H, supported by and passing through one or both of the side plates C D' of the chest A. My valve G is made hollow, providing a passage G' through it from end to end, as shown. The rock-shaft H may be worked by well-known mechanism and is obviously provided with suitable stuffing-boxes and bearing in the sides of the chest. 55

It will be seen that my valve G extends from end to end of the valve-chest and has its ends seated at all times steam-tight by suitable packing, on projected detail view, upon the inner surfaces F, adapted to form communication with the exhaust-ports F² at both ends of the valve-chest and upon oscillation cover and uncover the feed-ports, as will appear farther on. 60

I would have it understood that my invention comprehends either forming the whole valve-seat B in one piece with the engine-cylinder or separate therefrom; also, that the top D and side D' of the valve-chest may consist of separate pieces or be formed integral, 70 as found desirable. It will be further noticed by reference to Fig. 3 of the drawings that my valve G does not extend completely across from side to side of the steam-chest. With such construction free passage of steam is 75 permitted around and under the valve, thereby insuring perfect balance.

With the parts above described and a steam-inlet I the operation of my improved oscillating valve is as follows: When the piston J is 85 at the forward end of the engine-cylinder, as indicated in Fig. 1, the valve G will be in position with its passage-way G' connecting both exhaust-ports F² and the feed-port F' at the far end of the cylinder from this position 90 of the piston. In this position of the piston J and upon return stroke thereof, as indicated by the arrow in Fig. 1, steam will feed direct from the steam-chest A, through the uncovered port F' in rear of the piston, and 95 exhaust through the far port F' and both ports F². At proper time the valve will be oscillated, uncovering the feed-port F' at the rear end of the cylinder, by valve-shifting mechanism well understood, with its passage- 100

way G' still forming communication between the ports F² at both ends of the cylinder, and also covering the port F' at the forward end of the cylinder, as indicated by its dotted position. In this position of the parts the port F' at the rear end of the cylinder will be uncovered, adapted to feed steam from the chest A direct to rear of the piston, and the valve G be in position covering the port F' at the forward end of the cylinder, and both ports F², with steam exhausting through the outlets F³, and so on to continue at each reciprocation of the piston and oscillation of the valve while the engine is in motion.

15 From the above description it is apparent that I provide a valve extending to each end of the cylinder with its passage-way at each oscillation in position providing direct exhaust-outlet, and thereby decreasing the clearance to a minimum outside of the cylinder. Other advantages exist in the peculiar construction of my special steam-chest and valve-seat, thereby providing simplicity of parts in addition to adaptation thereof to a 25 valve extending from end to end of the engine-cylinder, as invented by me.

Having thus fully described my invention, what I claim as new, and desire to secure by Letters Patent, is—

30 1. In combination with an engine-cylinder and a steam-chest having two sets of ports

with one set at each end of the said cylinder, and one port in each set adapted to feed and the other adapted to exhaust, an oscillating valve located within the steam-chest, having 35 a passage-way through it from end to end providing communication between the exhaust-ports of each set and one feed-port, substantially as described.

2. In combination with an engine-cylinder 40 and its steam-chest, feed and exhaust ports at each end of the cylinder, means adapted to put one feed-port in communication with both exhaust-ports, the said means consisting of an oscillating valve extending from end 45 to end of the steam-chest, and having a passage-way lengthwise through it, substantially as described.

3. In combination with an engine-cylinder, and its steam-chest, the latter having two 50 valve-seats, one at each end thereof, exhaust and feed ports in each valve-seat, an oscillating valve in said chest, extending from one valve-seat to the other and having a passage-way through it adapted to put in communication both exhaust-ports and one feed-port, and means adapted to oscillate said valve, substantially as described.

GEORGE LESLEY WACKEROW.
